UNITED STATES PATENT OFFICE.

JEREMIAH HORAN, OF NEW YORK, N. Y.

CONTAINER FOR PACKED POWDER AND FOODSTUFFS.

Application filed July 21, 1921. Serial No. 486,456.

To all whom it may concern:

Be it known that I, JEREMIAH HORAN, citizen of the United States, residing at New York, in the county of New York and

5 State of New York, have invented certain new and useful Improvements in Containers for Packed Powder and Foodstuffs, of which the following is a specification.

This invention relates to a container for 10 packaged foodstuffs such as cereals, being designed more particularly for use in connection with cereals or the like which are sold in paper or cardboard cartons.

The invention has for an object to provide 15 an improved container in which such cartons may be placed for protection from mice, rats, or vermin generally and which will permit of the material in the carton being readily withdrawn without removing the 20 carton from the container.

A further object of the invention is to provide a container of this sort which is arranged to snugly hold cartons of different sizes.

25 For further comprehension of the invention, and of the objects and advantages thereof, reference will be had to the following description and accompanying drawings, and to the appended claims in which the 30 various novel features of the invention are more particularly set forth.

Fig. 1. of the drawings is a plan view of a container constructed according to the invention.

35 Fig. 2. is a perspective view thereof.

Fig. 3. is a vertical sectional view thereof, taken on the line 3—3 of Fig. 1.

Fig. 4. is an end view partly in section on the line 4—4 of Fig. 3.

40 Fig. 5. is a fragmentary vertical sectional view showing a modified arrangement of the discharge door, this view being taken along the line 5—5 of Fig. 6.

Fig. 6. is a fragmentary plan view of this 45 modified arrangement.

As here shown my improved container is of a general rectangular shape suitable to contain the cartons in which breakfast cereals or the like are sold, having fixed bottom and top walls 10 and 11, side walls 12, and one fixed end wall 13, the other end wall being removable for insertion of the carton. A full carton is shown at 15 in position in the container, the carton having one edge cut off to provide an opening 16 through which the food is removed.

To provide for discharge of the food from the container the latter is provided at the edge formed by the junction of the top wall 11 and end wall 13 with a diagonal or inclined 60 discharge opening 18 which extends, as will be apparent, partly along each of said end and top walls. In inserting the carton in the container the discharge opening 16 formed by cutting off the edge is placed in 65 registry with the opening 18 in the container.

The opening 18 in the container is closed by a door 20 which, in the form of the invention shown in Figs. 1 to 4 extends diagonally of the container and is hinged at its upper edge to the top wall of the latter as at 21, and bears at its lower edge against the top edge of the end wall 13. Spring fingers 22, secured as by screws 23 to the top 75 of the container and bearing on the door 20, normally urge the latter to closed position.

To open the door 20 I provide a thrust bar 24 slidably held in a groove 25 in the under face of the top 11 of the container and having its forward end downwardly inclined and engaging in a slot in a bracket 27 fixed to the inner face of door 20.

At its rear end this bar 24 extends upwardly through a slot 28 in the top 11, being doubled forwardly upon itself as at 29, and then backwardly over the top in a series of parallel convolutions 30. At its extreme rear end this bar is formed with a down-turned tip 31 adapted to engage in any one 90 of a series of sockets 32 in the container top 11 to hold the door 20 open to such varying extents as may be desired.

In order to enable cartons of smaller size than the container to be fitted into the latter with the discharge opening therein closely adjacent the opening 18 in the container, the end wall of the container opposite to wall 13 is in the form of a movable plate 35 arranged to fit snugly in the container, this 100 plate preferably having a rubber lining 36 covering the edges and inner face thereof. Projecting inwardly from this plate are a pair of sharp spikes 37 which project into the carton 15 and hold the latter raised 105 above the bottom of the container when the vertical dimension of the carton is less than that of the container.

The plate 35 is adapted to be pressed against the rear wall of the carton to hold the latter securely in place, the plate being held in adjusted position by means of a lock-

ing bar 38 pivoted between its ends as at 39 to the plate and provided with a fin-like handle 40 whereby it may be swung to locking or unlocking position. In locking position this bar 38 extends horizontally between the side walls 12, being of a length to "bite" into the latter and so hold the plate 35 in position.

It is believed that the manner of use of my improved container will be readily understood from the above description. The wall plate will be removed when an empty carton is to be taken out of the container and a new one inserted, the carton being placed in the container as indicated in Fig. 3. The door may be opened for discharge of the material by pushing on thrust bar 24.

As will be apparent, the material in the container will be protected from damage by rodents or other vermin, while it can be readily withdrawn therefrom in such portions as may be desired, the container being shaken while in a partially or wholly inverted position to discharge the material therefrom.

While I have herein shown and described a preferred embodiment of my invention it is to be understood that various changes and modifications might be made in the construction without departing from the principle of the invention, and the right is reserved to all such changes and modifications as come within the spirit and scope of the invention as defined in the appended claims.

In Figs. 5 and 6 I have shown one modification in which the opening 18 in the container is closed by a door 20' of angular shape to conform to the general rectangular outline of the container, this door being operated as above set forth by the thrust bar 24. In this modification an opening 50 is formed in the top wall 11 adjacent the door 20'.

Having thus described my invention what

I claim as new and desire to protect by Letters Patent of the United States is as follows:

1. A container for packaged foodstuffs comprising a rectangular casing having a discharge opening at the top of one wall thereof, the opposite wall of the casing being in the form of a movable plate, and means for locking said plate at varying distances from the first wall, said means comprising a locking bar pivoted between its ends to said plate and adapted to bear outwardly against the inner faces of the side walls of the container at its ends.

2. A container for packaged foodstuffs comprising a rectangular casing having a discharge opening at the top of one wall thereof, the opposite wall of the casing being in the form of a movable plate, said plate carrying spikes projecting inwardly into said casing and adapted to project into the package confined between the said walls whereby a package of less vertical dimension than the interior of the container may be supported with its top adjacent the said discharge opening.

3. A container for packaged foodstuffs comprising a rectangular casing having a discharge opening extending along one edge thereof, and a door hinged to the upper edge of said opening, said door having an operating bar hinged thereto at its front end and extending rearwardly in a groove in the under face of the top wall of the container and then outwardly through an opening in said wall, said bar having its rear portion in the form of parallel convolutions and having downturned tip at its extreme rear end adapted to engage in any one of a series of sockets on the said wall.

In testimony whereof I have affixed my signature.

JEREMIAH HORAN.
